UNITED STATES PATENT OFFICE

170,618

RADIO CABINET

Samuel E. Adler, Chicago, Ill., assignor to Admiral Corporation, Chicago, Ill., a corporation of Delaware

Application April 22, 1953, Serial No. 24,632

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio Cabinet, of which the following is a specification, reference being had to the accompanying drawings, forming a part hereof.

Fig. 1 is a front elevational view of a radio cabinet, showing my new design, the handle thereof being extended;

Fig. 2 is a top plan view thereof;

Fig. 3 is an elevation view of that side of the cabinet which is opposite the side shown in Fig. 1, the handle being retracted;

Fig. 4 is an end elevational view, and;

Fig. 5 is a fragmentary sectional view taken on line 5—5 of Fig. 1.

The dominant features of my design reside in the portions shown by full lines of the drawing.

I claim:

The ornamental design for a radio cabinet, as shown and described.

SAMUEL E. ADLER.
